UNITED STATES PATENT OFFICE

2,598,132

SOUND REPRODUCING APPARATUS

Pierre P. Pattyn, Detroit, Mich., assignor, by
mesne assignments, to John A. Patroske

Application June 15, 1949, Serial No. 99,232

1 Claim. (Cl. 179—100.2)

1

This invention relates to a novel apparatus for reproducing and simulating any type of musical tones or sounds.

A musical sound of a given pitch consists of a fundamental tone of definite amplitude and a plurality of secondary amplitudes of different harmonics of the fundamental. While not all of these harmonics are perceptible in themselves, they are all necessary in establishing the timber, quality and color of true musical notes. It is, therefore, an object of this invention to reproduce these musical tones or sounds with extreme fidelity.

Another object of this invention is to provide apparatus for creating sustained and percussion sound effects.

A further object of this invention is to provide apparatus in which tones or sounds are produced by translating electrically originated and controlled current pulsations into sound.

A further object of this invention is to provide apparatus in which the tuning is mathematically accurate.

A further object of this invention is to provide apparatus for producing musical notes and sounds which will have all the characteristics of the original instrument.

A further object of this invention is to provide a method of electrically producing a wider variety of tone qualities than has heretofore been possible in the art.

In an embodiment of the invention the musical notes and sounds are recorded on an endless tape of non-magnetic characteristic, with the tape having coated thereon or impregnated therein ferro-magnetic material or particles.

With the above and other objects in view, my invention consists in the arrangement, combination and details of construction disclosed in the drawing and specification, and then more particularly pointed out in the appended claim.

In the drawing,

Figure 1 is a detail side elevation, partly diagrammatic, of an electronic reproducing means for one note, constructed according to an embodiment of this invention.

Figure 2 is a plan view, partly broken away, of the device.

Figure 3 is a fragmentary sectional view taken on the line 3—3 of Figure 1.

Referring to the drawing, the numeral 10 designates generally a base which has fixed adjacent one end thereof a reel support 11. A reel or grooved wheel 12 is rotatably carried by the support 11, being mounted on a shaft 13 which

2

is fixedly carried by the support 11. A second grooved wheel 14 is disposed adjacent the opposite end of the base 10, being mounted on a shaft 15 which is fixed to a rock lever 16.

The rock lever 16 is rockable on a shaft or pin 17 which is carried by an upstanding support 18 fixed to the upper side of the base 10. An endless web or band 19 engages about the wheels 12 and 14 and the web or band 19 is extended over a stationary electronic pickup member generally designated as 20. The pickup member 20 is an electro-magnetic pickup member and is mounted on an upstanding standard or support 21 which is fixed to the base 10.

The web or band 19 is preferably formed of paper which has embedded therein metal particles 22 which are initially magnetized at the time a note or tone is recorded.

The pickup member 20 is connected by means of conductors 23 and 24 to an audio amplifier 25 of conventional construction, and the latter is connected to a loud speaker 26 which is also of conventional construction. The conductor 24 has interposed therein a switch generally designated as 27, embodying a stationary contact 28 and a movable contact 29. The movable contact 29 is associated with a rock lever 30 which is constructed in the form of one of the keys of an instrument similar to an organ or piano.

The web or band 19 is maintained substantially taut by means of a spring 31 which is connected at one end to the rock lever 16, and is connected at the other end, as indicated at 32, to the base 10. The band or web 19 is moved over the electro-magnetic pickup 20 by means of a shaft 33 connected with a motor 34. The shaft 33 bears against a rim or ring 35 carried by a driving wheel 36 which is fixed relative to the wheel or roller 12. In the present instance the shaft 33 is adapted to be rotated continuously, and the band 19 is movable continuously over the electro-magnetic pickup member 20. It will be understood that there will be as many bands and electro-magnetic pickups as there are notes or keys in the instrument, and selected ones or groups of the electro-magnetic members 20 will be electrically connected with the audio amplifier 25 and the speaker 26, as may be desired by depressing of selected ones or groups of the keys 30.

The electro-magnetic member 20 includes a core 37 disposed between a pair of non-magnetic members 38 and provided with an air gap 39 over which the corded web or band 19 is adapted to move. As the magnetized metal particles 22 pass over the air gap 39, the magnetic force in the par-

ticles 22 will activate the electro-magnetic member 20 at the time this member is energized by closing of switch 27 so that the recorded note or tone on web or band 19 will be communicated to audio amplifier 25.

The band or web 19 is initially placed on a recording device (not shown) wherein the actual note or tone of a particular musical instrument is recorded. This note may be recorded from instruments of various types.

In the use and operation of this device, the motor 34 is energized to continuously rotate shaft 33 so that web or band 19 will be in continuous movement over electro-magnetic pickup member 20. When key 30 is depressed, movable switch member 29 will engage contact 28 to close to electric current from audio amplifier 25 to pickup member 20. When the electric current is completed from pickup 20 to amplifier 25, the previously recorded note or tone carried by particles 22 will be communicated to amplifier 25 and from amplifier 25 the note or tone will be communicated to the loud speaker 26.

With a device of this kind, the actual note or tone of a particular instrument will be reproduced in a loud speaker so that the reproduction of the note or tone will not be of synthetic characteristic after the manner of the notes or tones which are produced through radio tubes which are placed in oscillation after a well known manner.

I do not mean to confine myself to the exact details of construction herein disclosed, but claim all variations falling within the purview of the appended claim.

What I claim is:

A music reproducing means comprising a base, an upstanding support fixed to said base, a

grooved wheel rotatably carried by said support, a drive wheel fixed relative to said grooved wheel, a second grooved wheel spaced from said first named grooved wheel, a support for said second named grooved wheel, means pivotally mounting said second named support on said base, an endless fibrous tape engaging about said grooved wheels, magnetized metal particles embedded in said tape, an electro-magnetic pickup carried by 10 said base and disposed in juxtaposition to said tape, a spring engaging said second named support for maintaining said tape taut, a resilient ring carried by said drive wheel, and operating means engaging said ring for rotating said drive 15 wheel.
